UNITED STATES PATENT OFFICE.

CHARLES W. GIRVIN, OF PHILADELPHIA, PENNSYLVANIA, ASSIGNOR TO GIRVIN ELECTRICAL DEVELOPMENT COMPANY, LTD., OF HONOLULU, TERRITORY OF HAWAII, A CORPORATION OF THE TERRITORY OF HAWAII.

DIRECT-CURRENT APPARATUS.

1,286,587.

Specification of Letters Patent. Patented Dec. 3, 1918.

Application filed August 26, 1915. Serial No. 47,499.

To all whom it may concern:

Be it known that I, CHARLES W. GIRVIN, a citizen of the United States, residing at Philadelphia, in the county of Philadelphia and State of Pennsylvania, have invented certain new and useful Improvements in Direct-Current Apparatus, of which the following is a specification.

My present invention relates to improvements in direct current apparatus, and more particularly to apparatus of this type adapted to operate in connection with currents of high potential.

The present invention is an adaptation of the general principles relating to this type of apparatus set forth in the patent granted to me September 5, 1916, No. 1,196,773, in which I employ a predetermined number of open-circuit armature coil-units, and a commutator so arranged as to maintain the units constantly in series relationship through the commutator acting individually on each unit, the commutator maintaining all the units in a constantly closed circuit, the commutator 25 in the form of apparatus shown in said companion application embodying a plurality of segments extending in peripheral and longitudinal rows, the segments having a prearranged system of connections with each other 30 and a prearranged system of contact connection with the coil-units.

In the present invention the relative arrangement of segments is changed in a manner to more closely approach in form the general type of rectifying apparatus, without, however, affecting the general principle referred to in said companion application, thereby simplifying to some extent certain structural features, thereby reducing the cost 40 of manufacture of certain types of apparatus of this general type.

Another feature is the ability to readily provide the necessary insulation between segments of the rectifying apparatus to meet 45 the conditions of high voltage working.

Another feature is the ability to provide groups of coil-units, each group having the characteristics referred to and capable of being put in series or parallel relationship, or 50 in a combination of these connections; similarly, taps may be employed and thus enable various voltages to be obtained independent of field excitation or speed variations.

To these and other ends, the nature of which will be readily understood as the invention is hereinafter disclosed, said invention consists in the improved construction and combination of parts hereinafter fully described, illustrated in the accompanying drawings, and more particularly pointed out 55 in the appended claims.

In the accompanying drawings, in which similar reference characters indicate similar parts in each of the views,

Figure 1 is a diagrammatic view showing 65 a simplified arrangement of segments adapted to carry out my invention.

Fig. 2 is a similar view showing the parts as angularly moved.

Fig. 3 is a diagrammatic view showing a 70 part of the structure of Fig. 1 on an enlarged scale.

Fig. 4 is a view similar to Fig. 3 showing the parts more particularly adapted for high voltage conditions, the segments being in 75 the position coincident with maximum voltage in the coil-unit.

Fig. 5 is a view similar to Fig. 4, but showing the position of the segments during commutation of the current in the coil-unit. 80

Fig. 6 is a view similar to Figs. 4 and 5 with the segments at an intermediate position.

Fig. 7 is a diagrammatic view showing a 85 modified arrangement of the segments.

Fig. 8 is a view similar to Fig. 7 with the segments angularly moved.

Fig. 9 is a diagrammatic view showing the application of the invention adapted for 90 use with a four pole machine.

Fig. 10 is a diagrammatic perspective view showing the general application of the invention.

Fig. 11 is a diagrammatic view showing 95 an arrangement in which a transformer forms part of a coil-unit circuit.

Fig. 12 is a diagrammatic view showing an arrangement in which a tap is inserted within the circuit.

Fig. 13 is a detailed sectional view showing 100 one way in which the segments may be mounted and connected.

Figs. 14 and 14^a are detail sectional and side elevational views respectively of a modified way of mounting and connecting the segments. 105

The present adaptation of the invention disclosed in the said companion application is especially adapted for use in connection with continuous currents of high potential 5 wherein the amperage is comparatively small. Examples of such uses are to be found in connection with electrical precipitation, X-ray work, etc., although the invention is not limited to such fields, being 10 capable of use where larger currents are desired. Where the current is small and the voltage is high, as for instance, in machines having voltages of from 40,000 to 100,000, as required for the above mentioned uses, the 15 necessity for a large number of individual segments and the small cross-section of conductor connecting the segments, render the general arrangement of the companion application somewhat expensive to manufacture, 20 since the segments are small and require considerable care in assembling.

In the present form I employ a structure more closely approaching the general type of rectifier segments, an example of which 25 is shown in Fig. 3, in the form of the segments, these segments being spaced apart. For the purpose of explanation, I will refer to these pairs of segments as segment rings, in contra-distinction to the collector 30 rings hereinafter referred to. The connections of this segment ring within the apparatus, however, differ from the usual form of such apparatus as will be more clearly understood from the showing of Fig. 1.

35 In Fig. 1, C^1 , C^2 , C^3 , C^4 and C^5 represent independent sources of alternating E. M. F.'s, such, for instance, as may be provided by the use of open-circuit armature coil-units; being similar in this respect to the 40 coil-units of the companion application. Each coil-unit has its terminals in the form of brushes 15, preferably arranged in the form shown in this figure, diametrically opposite each other, the brushes of a coil- 45 unit operating in connection with the pair of segments forming a segment ring, each coil-unit thus having its individual segment ring, the segment rings of the several coil-units being preferably arranged on a common axis and having angular positions relative to each other in correspondence with the similar relative positions of the armature coil-units, thus bringing the commutation positions of the segment rings in proper 50 relation with the brushes 15 at the instants of reversal of E. M. F.'s in the coil-units. A commutating position is shown at 20 in Fig. 1, coil-unit C^1 being shown as in short-circuit. The succeeding coil-units are shown 55 as of different phases, the several phases having a definite phase relationship, the angular positions of the segment rings being arranged accordingly.

One terminal of the circuit is indicated at 60 T being in the form of a collector ring, the

opposite terminal being also a collector ring indicated at T^1 . As shown, collector ring T is permanently connected to segment a of segment ring 20, segment b of this ring being connected to segment a of segment ring 21, this similar arrangement continuing through segment rings 22 and 23 into segment ring 24, segment b of this ring being connected to collector ring T^1 .

By this general arrangement a closed series circuit extends from terminal T to terminal T^1 , coil-unit C^1 being indicated as in the short-circuit position with its current undergoing commutation, the remaining coil-units being connected in series through the several connections between the segment rings, with the E. M. F. of each coil-unit in agreement with the direction of current flow in it.

As shown, the segments b of the several rings are permanently connected with the segments a of the succeeding rings, thus placing these segments as pairs of segments, these pairs in turn being connected by the coil-units, the latter each connecting segments a and b of its respective segment ring.

Fig. 2 illustrates the changes due to the angular movement of the group of segment rings. In this view the E. M. F.'s of the coil-units C^5 and C^4 are shown as having been reversed, coil-units C^3 being in its short-circuit position, coil-unit C^1 having passed from the short-circuit position of Fig. 1. As will be seen, the series relationship of the coil-units has been maintained, while at no time has the circuit been opened.

As shown in Fig. 10 the armature is stationary, the field magnet system rotating, the segment rings being mounted on the shaft 30 of the field magnet system, the latter being indicated at 31 and the armature at 32. As shown, the magnet system may include commutating poles as in the ordinary type direct current machine. While I have referred to the coil-units as being armature coil-units, the arrangement is capable of use in connection with other sources of alternating E. M. F.'s. For instance, as in Fig. 11, I may interpose a transformer with the coil-unit. Or the rectifying structure may have as sources of alternating E. M. F.'s the secondaries of a polyphase transformer, the primary of which may be supplied by the ordinary alternating current line, the rectifying structure being driven by a synchronous motor; or the primary of the polyphase transformer may be supplied by a separate alternating current generator, the rectifying structure being mounted on the same shaft with the generator.

As will be understood, this arrangement is applicable for use with a multiplicity of coil-units, the E. M. F. of each coil-unit be-

ing of different phase from all of the E. M. F.'s of the other units, or the E. M. F.'s of all may have the same phase.

For instance, in Fig. 1 I have shown the use of five coil-units, in Fig. 7 the use of four coil-units, and in Fig. 9 the use of three coil-units. Obviously the number of coil-units may be increased or decreased as desired to meet different working conditions, some uses permitting and possibly requiring a more or less pulsating direct current, while other uses require a practically continuous direct current.

As in the usual rectifying structures, the comparatively close arrangement of the segments *a* and *b* limits the maximum voltage which may be used per coil-unit, the adjacent ends of these segments having a difference in voltage equal to the voltage of the coil-unit. For this reason I prefer, in the case of high voltages, to arrange the spacing of the segments of a ring as shown more particularly in Figs. 4, 5 and 6, thus placing an extended space between the adjacent ends 25 of segments, this space being sufficient to prevent arcing over from one segment to the other, the length of the space being proportionate in each case to the maximum voltage of the coil-unit. To maintain the circuit closed during the commutation of the current in a coil-unit, the action provided by the bridging of the space between segments in Fig. 3 by brushes 15, I prefer to employ a pair of brushes 15^a electrically connected, in place of each brush 15. As shown in Fig. 4, corresponding brushes of the pairs should be spaced apart a distance equal to or greater than the distance between the adjacent segments, while the two brushes 40 of a pair should be spaced apart a distance equal to or less than the arc length of a segment, the minimum segment arc length being substantially equal to one fourth the circumference of the ring, the distances between 45 brushes being considered as the distances from center to center of the arc of contact of the brushes.

As shown in Figs. 4, 5 and 6, this arrangement prevents opening of the circuit, one of a pair of brushes at least being in contact with the proper segment at all times, as in Fig. 6, both brushes of a pair being in contact with the same segment when the coil-unit is at its maximum voltage, as in Fig. 4, the brushes joining opposite segments in the short-circuit position shown in Fig. 5, it being understood that the connections with adjacent rings are as in Figs. 1 and 2.

In Figs. 7 and 8, a slightly different arrangement is employed, the segment ring of a coil unit being replaced by two segment rings, each consisting of a pair of segments, *d*, *d*, Figs. 7 and 8, these segments being mounted diametrically opposite and concentrically, and being electrically connect-

ed, as at *x*, but so mounted that a brush or contactor placed to contact one segment would at no time contact the other segment. This is accomplished by mounting the segments in different planes when they are of same diameter, and in the same plane, as shown in these figures only when they are of different diameters. In this arrangement, each coil-unit terminal is composed of two brushes or contactors, the two operating with adjacent segment rings as shown, and the two brushes of the other terminal operating with the same two segment rings. As will be seen, with the exception of the instants of zero E. M. F. in the respective coil-unit, when all four terminal brushes of the coil-unit are in contact with segments and hence short-circuited, only one brush of each terminal pair is in contact with a segment, but at no time are both brushes of a terminal pair out of contact. Thus every coil-unit is always in the circuit and in series with all the other units and the circuit as a whole is constantly closed.

The circuit terminals, T³ and T⁴, Figs. 7 and 8, are each formed of a pair of brushes in order to be in continuous contact with the pair of segments the terminal operates with. The segment rings are preferably mounted on a common axis, and angularly positioned relative to each other in correspondence with the difference in phases of the coil-unit E. M. F.'s. In Fig. 7 coil-unit C⁶ is shown as in the short-circuit position, coil-units C⁷, C⁸ and C⁹ being out of such position, the coil units all being connected in series with the circuit constantly closed. In Fig. 8 the segment rings are shown as having been moved angularly, coil-unit C⁶ now out of short-circuit, the coil-unit C⁸ being in short-circuit, and the angular movement not affecting the series connection of the coil-units.

In Fig. 9 I have shown an amplified arrangement of the structure of Fig. 1, the segment rings in this arrangement each being formed of four segments, opposite segments of the ring being permanently connected together electrically, the spacing of the segments in this instance being of the type shown in Fig. 4. The action of the apparatus in fulfilling the conditions is substantially similar to the arrangement of Figs. 4, 5 and 6, the coil-units being short-circuited at proper times and being maintained in series relationship without opening the circuit. This arrangement is adapted for use in connection with four pole apparatus operating at equal speed with the rectifying structure. Obviously, the arrangement may be employed with a two pole or an eight pole apparatus, the rectifying structure operating at half or double the speed of the apparatus respectively; in this respect, the structure of Figs. 1 to 6 may operate in connec-

tion with four pole apparatus if the rectifying structure is driven at double the apparatus speed. It will be readily understood that the rectifying structure may be used in connection with six pole or other multipolar apparatus by arranging the segments to correspond.

As will be readily understood, the rectifying structure may be duplicated, thus forming similar groups of coil-units, the groups being available for independent, or series, or parallel, or series-parallel, operation, as desired. Or, if desired, taps may be inserted within the group circuit by connecting a collector or slip-ring to the proper permanent connection of the segments, this being illustrated in Fig. 12 at R.

It will be understood, of course, that the voltage at slip ring R is substantially the voltage of the series-connected coil units whose segment rings are located in advance of the slip ring and necessarily less than the total voltage of the entire circuit at the outgoing terminal.

The rectifying structure may be formed in any suitable manner, one form of which is indicated in Fig. 13, which shows a portion of a structure in which the segments are peripherally mounted. In Figs. 14 and 14^a I have shown the segments as mounted on the opposite sides of a disk.

The brushes may be of any suitable contact type, or may be in the form of bridge pieces arranged as close as possible to the segments so that spark-gaps are formed across which the current may pass, both forms falling within the term contactors.

While I have herein shown and described various ways in which the principles of my invention may be carried out, it will be readily understood that changes and modifications therein may be required or desired to meet the exigencies of use, and I desire to be understood as claiming the right to make any and all of such changes and modifications for such purposes as the same may fall within the spirit and scope of the invention as expressed in the accompanying claims.

Having thus described my invention, what I claim as new is,—

1. In direct current apparatus, a plurality of sources of alternating E. M. F.'s having definite phase relationship, contactors forming terminals for said sources with each terminal embodying a pair of contactors, and a rotating rectifying device having connected segments adapted to coöperate with said contactors to place said sources constantly in a closed series circuit, said segments being maintained constantly in circuit.

2. In direct current apparatus, a plurality of sources of alternating E. M. F.'s having definite phase relationship, contactors forming

ing terminals for said sources with each terminal embodying a pair of contactors, and a rotating rectifying device having connected segments adapted to coöperate with said contactors to place said sources constantly in a closed series circuit, said segments being maintained constantly in circuit, said device acting individually on each source.

3. In direct current mechanism, a plurality of sources of alternating E. M. F.'s having definite phase relationship, contactors forming terminals for said sources with each terminal embodying a pair of contactors, a rotatable rectifying device adapted to coöperate with said contactors to place said sources constantly in a closed series circuit, said device having individual segments constantly in circuit and connected in pairs, each source being adapted to connect pairs through the operation of its contactors with the segments.

4. In direct current mechanism, a plurality of sources of alternating E. M. F.'s having definite phase relationship, contactors forming terminals for said sources with each terminal embodying a pair of contactors, a rotatable rectifying device adapted to coöperate with said contactors to place said sources constantly in a closed series circuit, said device having individual segments constantly in circuit and connected in pairs, each source being adapted to connect pairs through the operation of its contactors with the segments, said device having its segments relatively arranged to cause the terminal contactors of a source to operate normally with segments of different pairs and to coöperate combinedly with the segments of both pairs during the period of commutation of the current in the source.

5. In direct current mechanism, a plurality of sources of alternating E. M. F.'s having definite phase relationship, contactors forming terminals for said sources with each terminal embodying a pair of contactors, a rotatable rectifying device adapted to coöperate with said contactors to place said sources constantly in a closed series circuit, said device having individual segments connected in pairs, each source being adapted to connect pairs through the operation of its contactors with the segments, said device having segments of adjacent pairs angularly spaced a distance sufficient to give a factor of safety against arcing over between segments from high potential in the source connecting the segments, while maintaining the circuit closed.

6. In direct current mechanism, a plurality of sources of alternating E. M. F.'s having definite phase relationship, contactors forming terminals for said sources, a rotatable rectifying device adapted to coöperate with said contactors to place said sources constantly in a closed series circuit, said

device having individual segments connected in pairs, each source being adapted to connect pairs through the operation of its contactors with the segments, each terminal of 5 a source having a pair of contactors angularly spaced apart, the segments coöperating with said contactors having lengths and being relatively positioned to permit both contactors of a terminal to coöperate with 10 a single segment at maximum voltage and with both segments at minimum voltage of the source.

7. In direct current mechanism, a plurality of sources of alternating E. M. F.'s having 15 definite phase relationship, contactors forming terminals for said sources, a rotatable rectifying device adapted to coöperate

with said contactors to place said sources constantly in a closed series circuit, said device having individual segments connected 20 in pairs, each source being adapted to connect pairs through the operation of its contactors with the segments, said device including a slip ring connected to a pair connection and adapted to act as a voltage tap 25 device.

In testimony whereof I affix my signature in the presence of witnesses.

CHARLES W. GIRVIN.
